UNITED STATES PATENT OFFICE

151,374

DESIGN FOR A DRAWER PULL

William A. Kendall, Winston-Salem, N. C., assignor to The Bassick Company, Bridgeport, Conn., a corporation of Connecticut

Application February 28, 1948, Serial No. 144,803

Term of patent 14 years

(Cl. D10—8)

To all whom it may concern:

Be it known that I, William A. Kendall, a citizen of the United States, residing in Winston-Salem, in the county of Forsyth and State of North Carolina, have invented a new, original, and ornamental Design for a Drawer Pull, of which the following is a specification, reference being had to the accompanying drawings, forming part thereof.

Fig. 1 is a front view of a drawer pull showing my new design;

Fig. 2 is a top view thereof; and

Fig. 3 is a side view thereof.

I claim:
The ornamental design for a drawer pull, substantially as shown.

WILLIAM A. KENDALL.
